United States Patent Office

Des. 221,190
Patented July 13, 1971

221,190

BOAT

Gerald G. Bonneson, 418 Main St., and James L. Juhl,
108 Countryview Drive, both of Hudson, Iowa 50643

Filed Feb. 16, 1970, Ser. No. 21,458

Term of patent 14 years

Int. Cl. D12—06

U.S. Cl. D71—1

FIG. 1 is a rear perspective view of a boat showing our new design;

FIG. 2 is a front elevational view thereof;

FIG. 3 is a side elevational view thereof;

FIG. 4 is a top plan view thereof; and

FIG. 5 is a rear elevational view thereof showing our design.

We claim:

The ornamental design for a boat, substantially as shown.
